CLAIM

The ornamental design for a static balancing valve, as shown and described.

DESCRIPTION

FIG. 1 is a top perspective view of a static balancing valve showing our new design;

FIG. 2 is a front view thereof;

FIG. 3 is a back view thereof;

FIG. 4 is a top view thereof;

FIG. 5 is a left side view thereof;

FIG. 6 is a right side view thereof; and,

FIG. 7 is a bottom view thereof.

The broken lines in the figures show features of the static balancing valve that form no part of the claimed design.
